CLAIM

The ornamental design for a combination reservoir and misting fan with a solid sidewall, as shown and described.

DESCRIPTION

FIG. 1 is a front elevational view showing my new design for a combination reservoir and misting fan with a solid side wall;;

FIG. 2 is a left side elevational view;

FIG. 3 is a rear elevational view;

FIG. 4 is a right side elevational view;

FIG. 5 is a top plan view;

FIG. 6 is a bottom plan view; and,

FIG. 7 is a perspective view.

The broken line showing of environmental structure in FIGS. 1-4 and 7 is for illustrative purposes only and forms no part of the claimed design.
